ATTORNEY

UNITED STATES PATENT OFFICE.

CARL S. DAHL, OF DULUTH, MINNESOTA.

LATCH-HOOK.

1,358,708.

Specification of Letters Patent. Patented Nov. 16, 1920.

Application filed February 10, 1920. Serial No. 357,616.

To all whom it may concern:

Be it known that I, CARL S. DAHL, a citizen of the United States, residing at Duluth, in the county of St. Louis and State 5 of Minnesota, have invented certain new and useful Improvements in Latch-Hooks, of which the following is a specification, reference being had therein to the accompanying drawing.

10 This invention relates to hooks and has special reference to a locking hook for use in holding two ends of a chain together and is particularly designed for use in connection with anti-skid chains used on auto- 15 mobile wheels.

The principal object of the invention is to produce an improvement upon the hooks as are commonly used for such purpose.

Another object is to produce a hook of 20 this character the accidental unlocking of which is rendered practically impossible.

Other objects and advantages of the peculiar construction will appear in the further description thereof.

25 Referring to the accompanying drawings forming part of this application:

Figure 1 is a side elevation of my improved hook as applied to a chain and locked.

30 Fig. 2 is a similar view showing the hook unlocked and engaging the opposite ends of a chain, and

Fig. 3 is a plan view of Fig. 1 taken at right angles thereto and showing a portion 35 of the housing for the locking pin in section.

1 represents the body portion of the hook which comprises an elongated piece of metal bifurcated its entire length except at the 40 end to which it is permanently fixed to the chain 2 where it is provided with an enlarged hub-like portion 3 through which the pin or rivet 4, by which it is attached to the chain 2 passes. The opposite end 45 of the body portion is turned or bent from alinement from the main portion thereof forming a goose-neck termination of the body portion as indicated at 5. This is for the purpose of providing a pivotal support 50 as at 6 out of alinement with the main body portion 1 for the adjustable member or latch 7, the inner end of which latter is also of goose-neck form as at 8. The 55 opposite end of the latch 7 is of a shape to fit readily intermediate of the bifurcated

portions of the body 1 and is provided with a suitable transverse hole 9 which registers with a similar hole 10 extending through the body portion when the latch is closed. The extreme termination of the free end of 60 the latch 7 is inclined as at 11, which when the latch is closed rests normally against the inclined end 12 of the channel between the bifurcated portions of the body 1, this being for the purpose of preventing the 65 latch passing wholly through between the two halves of the body 1.

The hole 10 is provided upon one side of the body portion with a laterally projecting conically shaped enlargement or hub 70

13, the hole in the end of which is a reduced continuation of the hole 10, and is countersunk forming a suitable seat for the tapered head 14 of the locking pin or bolt 15 which is reciprocably mounted within the hole 75

10. The end of the pin which engages the latch when the hook is locked and extends through into the opposite side of the body 1 is larger in diameter than that portion 80

normally remaining within the hub 13 thus forming an annular shoulder upon the pin 85

as indicated at 16. Intermediate of this shoulder and the outermost end of the larger portion of the hole 10 is installed 90

an expansive spiral spring 17 which normally acts to keep the pin in its locked position and when in such position the head 14 of the pin forms a complete closure for the countersunk end of the hub 13 which results in a smooth flush outer termination 95 of the hub 13 and the pin being non-accessible from such point.

In construction the pin 15 is first completely formed without the head 14 when the spring 17 is applied to the reduced 95 end thereof and the pin applied to the hole 10 from the side of the body 1 opposite to that which carries the integral hub 13, then when by pressure the pin is held in its fully retarded position the head 14 may be formed 100 by upsetting or other suitable means.

By this arrangement it is evident that the only possible way of withdrawing the pin from engagement with the hole in the latch when the latter is in locked position, 105 is by the use of a pin, nail, match or the like thrust into the open end of the hole 10 upon the side of the body 1 opposite to that upon which the hub 13 is formed. In this manner the influence of the spring 17 110

may be counteracted and the latch raised after having been freed from contact with the pin and the same method must be employed in locking the latch in position, thus rendering it practically impossible for the latch to be either locked or unlocked without the use of some small article such as above referred to for forcing the pin backwardly against the spring.

10 It may be here stated that while this positive locking feature at first glance may seem objectionable, attention is called to the fact that the many losses, annoyances and damages resulting from the accidental 15 locking of such a hook are far more objectionable and to be avoided if possible.

From the peculiar semi-circular shape of the pivotal end of the latch 7 it is evident that the opposite free end of a chain to 20 which the hook is fixed may be engaged by the free end of the latch when in a slack position and drawn taut by the closing of the latch, as clearly illustrated in the drawings.

25 It is to be understood that various modifications and changes in the structure here

shown may be resorted to without departing from the spirit of the appended claim which is drawn to cover that portion of the invention deemed novel.

30

What I claim is:

A hook of the character described comprising a bifurcated goose-necked body portion, a goose-necked latch pivotally attached to the similarly shaped end of the body portion and registerable intermediate of the spaced parts of the body portion, a hole within the free end of the latch, transversely disposed holes through the body portion and with which the hole in the latch is registerable and a spring actuated bolt within the hole in the body portion for through engagement with the latch, said bolt being adjustable only by means axially applied thereto, substantially as described.

45

In testimony whereof I hereunto affix my signature in the presence of two witnesses.

CARL S. DAHL.
